DESIGN FOR A DUST SEAL FOR CHRONOMETERS

Ernest William Drescher, Manheim Township,
Lancaster County, Pa.

Application May 13, 1943, Serial No. 110,196

Term of patent 3½ years

To all whom it may concern:

Be it known that I, Ernest William Drescher, a citizen of the United States, residing in Manheim Township, in the conutry of Lancaster and State of Pennsylvania, have invented a new, original, and ornamental Design for Dust Seal for Chronometers, of which the following is a specification, reference being had to the accompanying drawing, forming part thereof.

Fig. 1 is a top plan view of a dust seal for chronometers, showing my new design;

Fig. 2 is a bottom plan view of the same;

Fig. 3 is a vertical sectional view through the center thereof.

I claim:

The ornamental design for a dust seal for chronometers, as shown.

ERNEST WILLIAM DRESCHER.
